UNITED STATES PATENT OFFICE.

DUNCAN JAMES McGAURAN, OF GERALDTON, WESTERN AUSTRALIA, AUSTRALIA.

TELEPHONE-CALL RECORDER.

1,128,019.

Specification of Letters Patent.

Patented Feb. 9, 1915.

Application filed May 21, 1914. Serial No. 839,933.

To all whom it may concern:

Be it known that I, DUNCAN JAMES McGAURAN, a subject of the King of Great Britain, residing at Brede street, Geraldton, in the State of Western Australia, Australia, accountant, have invented certain new and useful Improvements in Telephone-Call Recorders, of which the following is a specification.

10 This invention relates to telephone call recorders of the kind described in United States specification Serial No. 786220 wherein calls are automatically recorded and means are employed for penalizing a 15 subscriber not answering an exchange call within a predetermined time, by automatically causing a call to be recorded against the subscriber when the call is answered after such time limit.

20 In this construction an automatic, electrically controlled timing mechanism is employed to throw the call recording mechanism out of action for a predetermined time when the exchange calls subscriber and the 25 improvements comprising this invention consist of either mechanical or electrical means for arresting the mechanism of the timing train of gear when a subscriber has 30 answered an exchange call within a prescribed time limit until the conversation is concluded and the hook switch lowered.

The invention is illustrated by diagrammatic drawings of which—

Figure 1 illustrates the mechanical construction thereof and Fig. 2 a detail of construction thereof. Fig. 3 illustrates the electrical means that may be substituted for the mechanical construction.

Referring to Fig. 1 a contact 34 made by 40 a subscriber raising hook switch 2 when answering a call completes a circuit through battery 5 spring operated lever 28, frame F, and electromagnet S which operates the call recording mechanism S M as described in 45 co-pending application United States Serial No. 786220. For the same object the recording mechanism may be mechanically operated by the movement of the hook switch as described in said application.

50 The lever 28 of the mechanism is attached to an armature and is operated to release the gear of a timing mechanism T for a predetermined time limit by means of an electromagnet X energized when a contact is made 55 through an electromagnet E in the calling circuit C when completed by exchange call-

ing a subscriber, the object of the timing mechanism being to throw the recording mechanism out of action if subscriber answers a call within a prescribed time limit, 60 and to subsequently restore the recording mechanism S M so that the raising of the hook switch 2 will cause the recording mechanism to record a call as described in the aforesaid application. The engaging arms 65 28^a, 28^b of the lever 28 are adapted to be lifted from notches 29 in the gear of the timing mechanism when said lever is operated by electromagnet X to set the train of gear in motion until such time as the end 70 of the arms engage again with the notches.

According to the present improvements the contact 34 Fig. 1, closed by raising hook switch 2 completes the circuit of electromagnet S and causes lever 40 of the recording mechanism to be held against the stop 50 until the hook switch 2 is returned to normal and said contact 34 is opened.

Attached to the hook switch 2 is a lever constructed of hinged arms 51, 52 the latter 80 being pivoted at 53 Fig. 2. The end of the arm 52 is adapted to normally bear against a spring bar or spring-pressed bar 54 provided with studs 55 and 56 adapted to engage, when exchange calls subscriber and 85 the timing mechanism is released, respectively with the vane 31 of the timing mechanism and with one of a series of notches 57 formed in a disk 58 attached to one of the gear wheels of said timing mechanism gear 90 train and at a time just prior to the arms of lever 28 engaging the notches 29 so as to arrest said timing mechanism T. Upon subscriber completing conversation and hook switch 2 being lowered, bar 54 is pushed 95 outwardly by the lever arms 51, 52, and the studs 55, 56, are removed from vane 31 and one of the notches 57 respectively so that timing mechanism is momentarily released until the arms of the lever 28 again engage 100 with notches 29. By this mechanism if the subscriber answers the exchange call within the predetermined time limit no call is recorded against him but a call is recorded if subscriber lifts the switch hook after such time limit so that he is penalized for the delay.

The bar 54 may be automatically operated by electrical means as illustrated in Fig. 3 and for this purpose an electromagnet 65 is 110 employed and is adapted when energized to move a pivoted spring controlled lever 66

provided with an armature 67 which is adapted to release the spring controlled bar 54 so that its studs 55 and 56 arrest the timing mechanism as described in connection with Figs. 1 and 2. The electromagnet 65 is energized when lever 28 is operated by electromagnet X through an exchange call and hook switch 2 is raised during the time limit, the following circuit being completed 10 viz:—stop contact 68, wire 69, contact 34, battery 5; electromagnet 65 and lever 28. The subsequent lowering of the hook switch 2 opens the circuit and deenergizes electromagnet 65 so that lever 66 springs back and 15 engaging bar 54 removes the studs 55, and 56 respectively from the vane 31 and notches 57 of the timing mechanism with the result above described in connection with the purely mechanical construction.

20 I claim:—

1. In the telephone call recorder the combination with an automatic call recording mechanism and a timing mechanism adapted to be automatically set in motion for a predetermined time when the exchange calls, of 25 means for arresting said timing mechanism when a subscriber answers the call within such time limit.

2. In a telephone call recorder the combination with an automatic call recording mechanism and a timing mechanism adapted to be automatically set in motion for a predetermined time when the exchange calls, of 30 a spring controlled bar provided with arresting means adapted to engage with the gear of the timing mechanism when subscriber answers a call within such time limit.

3. In a telephone call recorder the combination with an automatic call recording 35 mechanism and an electrically controlled timing mechanism provided with a spring operated lever adapted to be automatically temporarily released to set the mechanism in motion for a predetermined time, when exchange calls, of a spring controlled bar provided with arresting means adapted to engage with the gear of the timing mechanism just prior to the stopping movement of the 40 said lever when subscriber answers a call within the prescribed time limit.

4. In a telephone call recorder the combination with an automatic call recording mechanism and a timing mechanism adapted to be automatically set in motion for a predetermined time when the exchange calls 45 and provided with a vane and with a disk formed with a series of notches, of a spring controlled bar provided with studs and adapted to be released to engage respectively 50 with said vane and one of said notches when the telephone hook switch is raised by sub-

scriber answering a call within the time limit.

5. In a telephone call recorder the combination with an automatic call recording 55 mechanism and a timing mechanism adapted to be automatically set in motion for a predetermined time when the exchange calls and provides with a vane and with a disk formed with a series of notches, a hinged 60 lever on the telephone hook switch adapted normally to bear against a spring controlled bar provided with studs said bar being adapted to be released to permit its stud to engage respectively with said vane and 65 notches when said hook switch is raised by subscriber answering a call within the prescribed time limit.

6. In a telephone call recorder the combination with an automatic call recording 80 mechanism and an electrically controlled timing mechanism provided with a spring controlled lever adapted to be automatically temporarily released to set said timing mechanism in motion, when exchange calls, for a 85 predetermined time, of a spring controlled bar provided with arresting means adapted to engage with the gear of the timing mechanism just prior to the stopping movement of the said lever when subscriber answers a 90 call within the prescribed time limit by raising the hook switch, said bar being operated through an electromagnet by a contact in a circuit closed by the raising of said hook switch.

7. In a telephone call recorder the combination with an automatic call recording mechanism and an electrically controlled timing mechanism provided with a spring controlled lever adapted to be automatically 95 temporarily released to set said timing mechanism in motion for a predetermined time, when exchange calls, of a spring controlled bar provided with arresting means adapted to engage with the gear of the 100 timing mechanism just prior to the stopping movement of the said lever when subscriber answers a call within the prescribed time limit by raising the hook switch, a spring controlled lever in engagement with said 105 bar and provided with an armature of an electromagnet energized by a contact in a circuit closed by the raising of said hook switch.

In testimony whereof I have hereunto set 110 my hand in presence of two subscribing witnesses.

DUNCAN JAMES McGAURAN.
